UNITED STATES PATENT OFFICE

LOUIS MARMONIER, OF LYON, FRANCE

STABILIZING APPARATUS FOR AEROPLANES

Application filed September 22, 1931, Serial No. 564,385, and in France September 16, 1930.

The present invention has for its object devices used together or singly for the purpose of ensuring the stabilization of the pitching and rolling of an aeroplane, as also its 5 automatic steering. Their application may be made on navigating apparatus producing the three automatic controls of the aeroplane, as well as on more simple steering apparatus only effecting longitudinal and transverse 10 stabilization or the automaticity of the rolling and of the direction.

These devices are constituted, on the one hand, by gyroscopic arrangements of patterns suitable to the navigating apparatus to be 15 produced. These gyroscopic devices which produce a horizon base and a bearing control, do not form the object of this invention. They are referred to in this specification only 20 with a view to the description of the various righting members with which they act in concert to automatically stabilize and direct the aeroplane.

The arrangement proper with which this patent deals comprises:

25 An "unlocking device" of the bearing control dealing with navigating in direction,

A "swinging corrector" and a "palette feeler", preventing slipping on the wings, which operate with the steering of the aile- 30 rons.

A "loss of speed signaller" having reference to depth steering.

The action of the righting members above mentioned, is co-ordinated by differential devices which in concert with the horizon base or the bearing control, permit of obtaining the automaticity of the controls of the action 35 on two or three of its evolutions. These co-ordinating mechanisms also form an object of 40 this patent.

The navigating apparatus which will be constructed by applying devices described in this patent may be of various patterns accord- 45 ing to the method of operation which will be chosen for the gyrostatis and the Servo-mo-

tors. In the text of this specification, and in the diagrammatic drawings annexed thereto, use will only be made of an electric device 50 ensuring the automaticity of the controls of the aeroplane on its three evolutions, but it would be also quite possible to construct on these devices, navigating apparatus working with compressed air or by vacuum, by modifying the manufacture accordingly.

The electric navigating apparatus, which is more particularly described in this specification and which is shown on the annexed drawings, effects the longitudinal stability caused by the automatic control of the depth rudder. The lateral stability is controlled 60 by the automatic tilting of the blade, and the direction of the aeroplane is controlled on its bearing line by the automatic control of the direction rudder. The pilot may also cause the aeroplane to rise or dive and carry out all 65 the turns which he considers useful by utilizing the automatic navigating apparatus.

As is proper, the control of the blades or ailerons and that of the directional rudder are connected one to the other during the 70 turns of the aeroplane in order to obtain a correct turn, and this special arrangement, as also the members correcting the turning or the slip on the wing constitutes one of the characteristics of this invention. The con-

trol of the directional rudder and the tilting of the ailerons takes place in connection with a horizon base on which rest its two rudders during the whole of the turns. The automatic control of the three controls is ensured 75 by electric, compressed air, or vacuum Servo-motors which, during disturbances of the equilibrium of the aeroplane, rest on a horizon base and a bearing control produced by a gyroscopic group counterbalanced on the 80 three dimensions of space and which controls consequently all the deviations of the aero- 85 plane in its three evolutions.

The horizon base which arises from this gyroscopic group is utilized to maintain the 90

course of flight of the aircraft in the longitudinal and lateral direction, to automatically brake the pitching and tossing, while the bearing control automatically keeps the 5 aeroplane in its line of flight.

The automatic navigating apparatus is, furthermore, provided with three special devices which act in accord with the horizon base, which itself is constantly in engagement 10 with the pitching and tossing Servo-motors. One of these devices called the "loss of speed signaller" deals more particularly with the longitudinal stability. It has for its object to register the minimum speed necessary to 15 sustain the aeroplane in the corresponding wind, in order to effect the diving of the aeroplane before it has reached the minimum of speed capable of causing its descent. It thus acts as an automatic righting device in combination with the horizon base.

The second device called the "turning corrector", controls the tilting of the aileron during the turning of the aeroplane, and determines the angle of inclination of the wing, 25 with respect to its speed and the radius of the path described, in order that the speed of the aeroplane remains in the central plane of the apparatus.

This "turning corrector" is constituted by 30 a mass which is displaced laterally in a horizontal plane and which operates in concert with the horizon base. It ensures at the same time the equilibrium of the gyroscopic group of three dimensions or of any other pattern, 35 which being pendulum are subjected to centrifugal forces during the turnings of the aeroplane. The "turning corrector" which also undergoes the effects of centrifugal force, is able to counterbalance these by a 40 suitable device which will be later described.

The action of the "turning corrector" is completed by a "palette feeler" which registers the direction of the side winds, and prevents slipping on the wing during the turnings where the actual direction of the wind, 45 with respect to the aeroplane which turns in the wind, varies at each instant. This palette feeler is in direct connection with the horizon base in such manner that it is in a constant vertical position, whereas the aeroplane inclines in the course of the turning. It is consequently independent of the latter, and can counterbalance it efficiently by modifying its angle of entry according to the 50 actual direction of the wind.

The automatic direction of the aeroplane in line of flight is obtained by the bearing control produced by the three dimension gyroscopic group shown in this patent, or by a 60 gyroscopic group of a different model. This control preserves the bearing by exciting the Servo-motor at the least deviation of the aeroplane in its straight trajectory. Nevertheless, it is advisable to release the bearing 65 control during the turning of the aeroplane,

for if it remains attached thereto it would be necessarily put out of order, being fixed in azimuth, while the aeroplane undergoes a gyratory movement. Consequently, the navigating apparatus is provided with a special device which has for effect to connect the bearing control with the directional Servo-motor during the flight of the aeroplane in a straight line, in order to preserve the bearing, and to disengage this control during the 70 turnings. Nevertheless, in spite of this disengagement, the excitation of the Servo-motor which controls the directional rudder, as also the control of this Servo-motor should remain at the disposal of the pilot, so that he 75 can carry out the turning automatically, in combination with the horizon base.

When the navigating apparatus only comprises the stabilization of the pitching and tossing, excluding that of direction, the stick which is utilized by the aviator to direct his aeroplane will be connected to the automatic navigating device of the aileron so that the turns may be carried out correctly and under 80 the same conditions as a three evolution navigating apparatus.

The gyroscopic group placed in equilibrium on the three dimensions of space, which will be dealt with in this patent to the exclusion of other gyroscopic devices the use of which may be intended, is that which forms the object of the French Patent 646,217 of the 9th May 1927, and which comprises several models of groups. That which is used in this 85 automatic navigating apparatus is the model 100 No. 1 of that patent. It is constituted by four gyrostats each reacting in a different plane in such manner that two of them place in equilibrium the group to the horizon. These are entitled "horizon gyrostats", for 105 they produce the horizon base, while the other two called "directional gyrostats" exert their inertia in azimuth and produce the bearing control which automatically directs the 110 aeroplane in its line of flight.

To this group has been added a device entitled "Direction recovery", the object of which is to keep the bearing control in a constant azimuthal plane, and in consequence to preserve to the aeroplane a definite direction. This direction recovery is put in movement on the slightest deviation of the aeroplane from its line of flight, which deviation produces the precession of the directional gyrostats which, in their turn, excite the direction recovery. The latter produces a couple contrary to the couple of deviation, in order to re-establish the bearing control in its original azimuthal plane. This bearing control acts in its turn on the directional Servo-motor to bring the aeroplane back into its line 115 of flight.

To this gyroscopic group are also applied all the improvements described in the four 120 certificates of addition connected with the 125

above-mentioned French patent, and in particular by the first certificate of addition dated the 30th November, 1929, the device entitled "Engagement and disengagement of the gyrostat" which permits of locking the gyrostats before their discharge and to then unlock them in order to give them full liberty of precession on their axes of rotation. This arrangement leaves the gyrostats in natural equilibrium on their precessional axes, and preserves intact their power of reaction in the azimuthal plane. From this certificate of addition, there is also applied the device entitled "Compensator of inertia of the pendulum masses", with the object of keeping the group in a state of equilibrium during the turnings of the aeroplane. On the other hand, if the automatic navigating device, instead of being actuated electrically as is hereafter described in this specification, were actuated by compressed air, the directional and stabilization gyroscopic group would benefit by the improvements pointed out in this first certificate of addition as regards the construction of the group.

The fourth certificate of addition to the above mentioned patent also contains devices which are of advantage to the gyroscopic group, particularly as regards the bearing control. The devices which are used in this steering device consist:

(a) In the braking of the group on its vertical pivots with the object of causing the precession of the directional gyrostats on the least change of bearing of the aeroplane, and to produce from this cause, the excitation of the direction recovery which re-establishes the bearing control in its original plane;

(b) In a device entitled "Compensator for retardation of precession", which has for its object to supplement the foregoing device and make it more efficient.

To facilitate the understanding of the description of the co-ordinating devices and registers of the relative wind which form the object of the present invention, three diagrammatic drawings naturally only given as examples, are annexed to this specification. These drawings only represent the navigating device actuated electrically, excluding the compressed air device, which can be constructed according to the same arrangements of principle.

Fig. 1 shows diagrammatically the electrical navigating device, as regards the automatic direction of the aeroplane on the bearing, and the lateral stability controlled automatically in direct flight and during the turns. This view also represents: the two half sections of the stabilizing gyroscopic group, of which one deals with the bearing control, and the other the horizon base; the unlocking device of the bearing control by the direction lever during the turnings of the aeroplane; the direction lever which controls

the turn; the turning corrector which neutralizes at the same time the effects of centrifugal force of the gyroscopic group mounted in pendulum; the "palette feeler" which registers the actual direction of the wind in which the aeroplane moves, this palette being in a constant vertical position by its connection with the horizon base; the differential mechanisms which co-ordinate the action of these members, while leaving them in constant engagement with the horizon base; the Servo-motors for tilting the ailerons and the directional rudder and their subjection to the switches which excite them.

Fig. 1bis is a continuation of Fig. 1.

Fig. 2 represents diagrammatically the depth steering device. The gyroscopic group figure in this by the half section which produces the horizon base. This figure also shows the hand lever which permits the aeroplane to be caused to rise or to dive; the "loss of speed signaller" which registers the minimum thrust and pull necessary to sustain the aeroplane to prevent the loss of speed and counterbalance this at the proper time; the Servo-motor of the depth rudder and its connection to the exciting switches; the differential mechanisms which co-ordinate the action of these members with the horizon base which serves to support the whole system.

Fig. 3 shows details of construction of the differential mechanisms which permit of unlocking the bearing control during the turnings of the aeroplane and of ensuring the automatic control as also the control of the directional Servo-motor both during the automatic control of the aeroplane on the bearing as well as during turning.

To facilitate the description which follows, the gyroscopic group placed in equilibrium on three dimensions, has been divided up into two half sections (Fig. 1): On the one hand, the half section which produces the bearing control and which comprises the two directional gyrostats *a* and *b*, as also the oscillating and pivoting suspension *g*; on the other hand, the half section of the group which improves the horizon base on which rests the automatic governing of the tilting under all circumstances both during straight flight as well as during turning. This same horizon base which is also applied to the depth steering (Fig. 2) comprises the two horizon gyrostats *c* and *d* which exert their inertia in the horizontal plane, and which are kept in constant equilibrium in this plane by the pendulum mass *f*, which, being always preponderant, re-establishes the horizontality of the group when this, for one cause or the other, oscillates on its suspension pivots.

This non-equilibrium is produced during accelerations of the aeroplane and principally in the course of turning in consequence of the prolonged action of centrifugal force. There is reason to neglect the non-equilibrium of

the group during the variations of relative speed of the aeroplane, for the horizon gyrostats *c* and *d* oppose at once their inertia reaction to an acceleration, the value of which 5 decreases, and the oscillation of the group resulting therefrom is rapidly deadened by the preponderance of the force of gravity. But it is not the same with the effect of 10 centrifugal force, during the turnings of the aeroplane, for this force, continuing over the whole duration of the turn, would put out of equilibrium the horizon base. It is therefore necessary to provide a special device which 15 counterbalances the influence of centrifugal force on this group.

In the navigating apparatus forming the object of this patent, this compensating device consists in a mass 1 of which the centre of gravity is situated, during the flight, in a 20 direct line on an axis 2 longitudinal to the bearing of the aeroplane. This axis which may pivot freely, is connected to the gyroscopic group by the lever arms 3 and 3' and the connecting rod 4. The mass 1 is mounted 25 on two square rods 5 and 5', along which it can slide laterally rolling on two rollers 7, of which only one is visible in the drawings. It is kept in its central position by two 30 springs 8 and 9. The mass 1 does not therefore oppose the action of gravity on the group, which is one of the conditions of 35 equilibrium of the horizon base. It is indifferent to the accelerations of the aeroplane but, on the other hand, being given its liberty of movement in the lateral direction and on a horizon line which is constant, it is susceptible to the action of centrifugal force, and can oppose the action of this same force 40 on the pendulum gyroscopic group. Furthermore, it serves as turning corrector, as will be later shown.

In the case where the aeroplane which flies 45 towards 6, would turn to the left for example following the arrow 10, the pendulum group of gyrostats is subjected to the action of 50 centrifugal force on the line 11, but at the same time the mass 1 is thrown towards 12 and, from the fact of its lateral displacement on the rods 5, 5', produces a couple 13 which opposes the couple 11, and which it 55 equals during the turnings of the aeroplane naturally on condition that the weight of the mass 1 is in proportion to that of the pendulum *f*, and that its displacement on the rods 5, 5' is suitably determined by the tension of the springs 8 and 9, which tension is adjustable as desired.

The mass 1, furthermore, reaches its position of equilibrium on the rods 5 and 5' 60 before the centrifugal force has been able to act on the group, for the gyrostats *c* and *d* oppose from the first their inertia to this force.

On the other hand, seeing that the gyroscopic group constitutes an inert mass placed

in equilibrium in the three dimensions of space, in the case where the two antagonistic couples 11 and 13 did not counterbalance each other, the predominant couple would only have a relative influence on the equilibrium of the group, for the two gyrostats *c* and *d* being fixed in azimuth, while the aeroplane rotates about them, the predominant couple acts sometimes on one of the faces of the plane of reaction of the gyroscopes, and 70 sometimes on their opposite face, so that it neutralizes itself during the turnings of the aeroplane. Also, when the latter again flies in a straight line, gravity having again become predominant, will counteract the oscillations of the group which might have been produced in the course of the turning. 75

Having at disposal a bearing control and a horizon base in constant equilibrium, if the aeroplane flies in a straight line, when it deviates in direction the bearing control will excite the Servo-motor which controls the directional rudder to bring it back automatically into its line of flight. 80

On the other hand, when the pilot desires 85 to turn the aeroplane, it will be necessary to automatically unlock the gyroscopic group, as otherwise the latter would be carried in the gyratory movement of the aeroplane and completely disengaged. 90

The automatic navigating device must therefore have a special mechanism fulfilling the following conditions:

(a) Subject the directional rudder to the bearing control, during the straight flight 100 of the aeroplane, in order to direct it automatically;

(b) Disengage the bearing control during the turning of the aeroplane, while leaving the directional Servo-motor, as also the 105 members for controlling this Servo-motor, at the disposal of the pilot, so that he can carry out the turning, while using the automatic navigation.

(c) This same mechanism must permit 110 the pilot to rectify the bearing of the aeroplane if there are produced deviations of route of small incidence, without the disconnecting of the bearing control of the automatic navigating device, as is necessary for 115 a complete turn.

This mechanism represented in Figs. 1 and 3, comprises a vertical spindle 14 which carries at its upper extremity a contact arm 15 which transmits the contact disc 18, which 120 terminals are connected to the two concentric contacts 16' and 17' and to the two fixed post current terminals 16'' and 17''. The spindle 14 rotates in a tube 19 fixed on the frame 20, and carries at its lower part a square base 14' in which can slide a disc 21 which normally is kept raised by a spring 22 which compresses it strongly against another disc 23. This latter is connected with the gyroscopic group by a bevel wheel 24 125 130

to which it is keyed, and another bevel wheel 25 connected directly by the spindle 25' to the group by two other bevel wheels not shown on the drawings. The spindle 14 is therefore attached to the gyroscopic group when the spring 22 acts on the disc 21, if not, the bevel wheel 24 and its disc 23 rotate freely on the spindle 14. This case arises when the disc 21 is attracted by an electromagnet 26 fixed to the frame 27 of the gyroscopic group, and consequently connected to the aeroplane. On the tube 19 is placed a double differential constituted by the planetarium 28 and a satellite 29. The latter can rotate about the tube 19 in consequence of its being mounted on a sleeve 29' pivoting on this tube.

On the sleeve is fixed the direction lever 30 which controls the automatic turning, to the right or to the left, of the aeroplane according to whether it is displaced to the right or to the left. The double differential is completed by a double planetarium 31, a satellite 32, and a planetarium 33, which is fixed to the contact disc 18. On the direction lever 30 is fitted a switch 34 which in pivoting in one direction or in the other direction closes the contact with two sectors 35 and 35' connected together and, on the other hand, to the electromagnet 26.

In consequence of this arrangement, when the direction lever 30 is in the position of rest, the bearing control being coupled to the spindle 14 and consequently to the contact arm 15, the aeroplane is automatically directed on its bearing, while the displacement of the direction lever 30 to the right or to the left magnetizes the electromagnet 26 which, attracting the disc 21, fixes the spindle 14 and its contact arm 15 on the frame 27. Owing to this, the spindle 14 being disengaged from the bearing control and being connected to the aeroplane, the pilot can carry out a turning with the aid of the navigating device, for the Servo-motor 36 of the direction rudder 37 remains in communication with the direction lever 30 by the differential 28, 29, 31, and by that 31, 32, 33, which is coupled to the rods actuating the Servo-motor 36 by a lever arm 43.

This device is complemented by a worm wheel 51, which is fixed to the planetarium 28 and which pivots in one direction or the other by means of a worm 30, the spindle 50' of which is within reach of the pilot. This movement of rotation has for effect to rotate the contact disc 18 through the intermediation of the double differential and consequently to vary the bearing of the aeroplane without it being necessary to disengage the bearing control.

In view of these devices, if the aeroplane which follows its flight towards 6, deviates to the left towards 10, the contact arm 15 comes into contact with the half sector 16 which excites the Servo-motor 36 which in-

duces, in its turn, the displacement of the direction rudder 37 following the arrow 40. This displacement is limited by the control rod system 39 which, moving towards 42, causes the arm 43 to rock, rotates the satellite 32 towards 44, and finally rotates the contact disc 18 towards 45, thus cutting off the current of the Servo-motor 36.

When, under the influence of the direction rudder 37, the aeroplane takes up again its line of flight, the reverse operations will take place until the moment when the direction rudder 37 again takes up its neutral position.

The automatic navigation of the aeroplane in the lateral direction and the braking of the rolling, are produced under similar conditions, but with this difference that the Servo-motor of the ailerons remains constantly in engagement with the horizon base which intervenes under all circumstances.

Seeing that the horizon base is shown by the planetarium 47, any lateral steering device therefore gravitates about this planetarium on which it is supported to ensure the automatic lateral stability, both when the aeroplane flies in a direct line, as well as when turning.

In the case where the aeroplane, commencing a rolling movement, would hang for example on the left wing, the two oscillating arms 48 and 49 being connected with the aeroplane, undergo the rolling and incline towards the right carrying with them in their displacement the satellites 52 and 54 towards 55 and 56, causing the planetarium 53 to pivot towards 57. But as the satellite 52 is in engagement with the planetarium 47 of the horizon base, the movements of rotation of the satellites 52, 52 and 54 come into equilibrium in the planetarium 53 and the planetarium 58 remains at the fixed point in spite of the rolling of the aeroplane. As this planetarium 58 is in engagement with the contact arm 59, the latter also remains at the fixed point, and subjected to the horizon base 47 without the double differential affecting this connection. But it is not the same with the contact sector 60 which is carried towards 66 by the rolling of the aeroplane in consequence of its connection to the controlling rods 65. Current taking is therefore established between the contact arm 59 and the contact 61, exciting the Servo-motor 62 which causes the ailerons 63 to turn towards 64, so righting the aeroplane. The tilting of the ailerons 63 is limited exactly to the angle of entry of the rolling with respect to the horizon base, by the control 63 which, moving towards 69, causes the contact sector 60 to pivot towards 67, cutting off the current at the proper time.

In righting towards the right, the aeroplane will produce the reverse action of the tilting Servo-motor and the ailerons will take up their nor-

mal position in the same degree as the aeroplane re-establishes its equilibrium.

To carry out a turning in the aeroplane, and in order that this may be correct, it is necessary that the speed remains in the central plane of the apparatus. It is therefore necessary that the thrust and the drag, place in equilibrium both the weight of the aeroplane and the centrifugal force which is exerted on it during the turning. The direction and tilting controls must therefore act in concert in order that the turning may be started, while the tilting of the ailerons inclines it on the wing with an angle of entry sufficient for the centrifugal force not to bring it out of its course. In the case of automatic navigation, such as this forms the object of the present invention, the intervention of the direction rudder and the tilting of the ailerons must take place simultaneously on the starting of the turning, and immediately after the disengagement of the direction control. But in order that the condition of turning may be fulfilled, it is indispensable to add to the automatic device a "turning corrector" which determines exactly the angle of entry corresponding to the centrifugal force acting on the aeroplane. This "turning corrector" which operates in concert with the horizon base, has for this reason an action defined and limited by the inclination of the aeroplane to this horizon base, on which rests the whole of the device.

The turning corrector of the automatic navigating device is the mass 1, which as has been previously stated, is displaced laterally during the turnings. This mass being only sensitive to centrifugal force which is exerted on it in a constant horizontal plane, registers exactly the value of the centrifugal force which acts on the aeroplane whatever may be the incidence of the angle of entry of the latter to the horizon. Consequently, if the aeroplane is to carry out for example a turn to the left, in the direction of the arrow 10 it is sufficient for the pilot to move the direction lever 30 to the right towards 30', not having to carry out any other operation for the turn to take place automatically and correctly up to the moment when it is necessary to again take up the direct line of flight, releasing the direction lever, which by means of a resetting device, not shown on the drawings, will automatically take up its neutral position.

In consequence of the movement to the right of the direction lever 30, the switch 34 excites the electromagnet 26 which has for effect to disengage the contact arm 15 of the bearing control and to connect this to the aeroplane in order to permit the turning.

In moving to the right, the lever 30 causes the satellite 29 to pivot towards 69' for it engages with the planetarium 28 which is connected to the aeroplane, the double planeta-

rium 31 pivots towards 70, the satellite 32 towards 44, and finally the contact disc 18 towards 45. The contact arm 15 then connects with the contact 17 which excites the Servo-motor 36, which operates a movement of the direction rudder 37 towards 41, causing the aeroplane to turn to the left. The operating rod system 39 which moves towards 71' and the satellite 32 which cause the contact disc 18 to pivot towards 71, limit the angle of entry of the rudder 37, the latter retaining this position for the whole of the turn, its angle of entry y^2 being equal to the angular displacement y of the correction lever 30.

At the same time, that this manœuvre takes place, the direction lever 30 displaces the rod 73 towards 74, which has the effect to cause the oscillating arm 49 to pivot towards 75, and to displace the planetarium 58 towards 76, the contact arm 59 towards 66, and putting it in communication with the contact 77.

The Servo-motor 62 being excited, tilts the ailerons 63 towards 78. The left wing sinks, and the aeroplane inclines in the direction of the turn, but in a certain proportion for the angle of entry of the ailerons 63 remains in relation to the angular displacement y of the direction lever 30, this angle of entry being limited by the controlling rod system 65 which, moving towards 75, cuts off the current at the proper moment by the contact sector 60 which pivots on its axis. As, on the other hand, the contact arm 59 is connected to the horizon base by the double differential 52, 53, 54, 58 its incidence to the horizontal plane can only reach the angle y of displacement of the direction lever 30. Thus, when the inclination of the aeroplane to the horizon corresponds to, or exceeds, this angle, the aileron 63 will cease to tilt or will tilt towards 64, if it exceeds this angle, in consequence of the reverse action of the Servo-motor 62.

At this moment, the "turning corrector" will intervene, as this comes into action from the moment that the aeroplane commences to turn. Owing to this, the mass 1 is projected horizontally to the right, towards 12, carrying with it in its displacement the rack 80 which causes the toothed sector 81 and the planetarium 82 to pivot towards 83. The rod 84 is pushed towards 85 as also the oscillating arm 48, carrying the satellite 52 towards 55', the double planetarium 53 towards 57, the satellite 54 towards 87, and finally the planetarium 58 and the contact arm 59 to which it is attached, towards 66, making connection with the contact 77, that is to say, in the sense of the tilting of the ailerons on the left wing, towards 78, this tilting being increased in proportion to the centrifugal force which acts on the aeroplane, which corresponds to that which acts on the turning corrector.

But this tilting cannot exceed a definite angle; for the whole of the arrangement being subject to the horizon base, if the angle of

entry at a turning were exceeded, which might produce a slip on the wing, independent of the loss of speed, the righting would take place at once in consequence of the reverse tilting of 5 the ailerons 63.

This slip on the wing takes place principally in the course of turning, when the angle of entry of the aeroplane on the wing is exaggerated with respect to its relative speed in 10 the wind. The actual direction of the wind with respect to the aeroplane varies at each instant during the turning, and the slip on the wing is produced in particular when the aeroplane, having fought against the wind and 15 having lost a portion of its real speed, a loss which is proportional to the actual speed of the wind, enters afresh into the wind's eye. At this moment, not having regained sufficient relative speed to support it, it slides on 20 the wing if the incidence of the angle of entry of the inner wing is too accentuated.

With a view to giving this angle of entry on the wing the incidence corresponding to the direction and actual speed of the wind, 25 there is added to the navigating lateral device a palette feeler 90, situated at the extremity of two arms 91, 91' fixed on two sockets 92, 92', which are carried on a vertical spindle 93 which pivots in the frame 30 94. This frame 94 itself pivots on an axis 95 longitudinal to the aeroplane, and the whole of this device is connected directly to the gyroscopic group by a rod system 96, 97 and the levers 98 and 99. In consequence of 35 this arrangement, the palette feeler 90 remains always vertical whatever may be the angle of entry of the aeroplane on the wing. It is placed in equilibrium statically by the counter weights 100, 100', and is held in the longitudinal axis of the aeroplane by counter 40 springs 101, 101'. In view of its constant vertical position, independent of the position of the aeroplane and of its angle of entry on the wing in the course of turning, this 45 palette feeler registers the direction and actual speed of the wind. Its indications are transmitted by the bevel wheels 102, 103 to a longitudinal spindle 104 which transmits them to a planetarium 105, which in its turn 50 acts on the excitation of the Servo-motor 62 to produce the tilting of the aileron 63 in one direction or the other.

If the aeroplane turns to the left towards 55 10, the palette feeler 90, in consequence of the relative speed of the aeroplane and of its change of bearing, is drawn along and pivots horizontally towards r , in proportion to this speed and to the curve of the trajectory of the turn, the incidence of entry being 60 adjustable at will by the counter springs 101, 101'. The variation of incidence of the palette feeler 90 causes the spindle 104 to rotate towards 106, and the planetarium 105 to pivot towards 107, which produces the tilting 65 of the aileron 63 towards 78, to increase

the angle of entry of the aeroplane on the wing.

But, if the wind v is strong, when the aeroplane having fought against this wind and having its actual speed reduced in proportion to the speed of this wind itself, if it pursues its turn towards 10, the wind commences to act on the palette feeler 90, the incidence of which it diminishes and even causes this latter to pass over to the incidence r' , if it has a high speed. In this case, the spindle 104 pivots towards 108, the planetarium 105 towards 109, tilting the aileron 63 towards 64, righting the aeroplane and diminishing its angle of entry on the wing, 70 so that the aeroplane enters into the wind's eye under conditions satisfactory for its lateral stability.

It is evidently necessary to co-ordinate the 75 respective action during the turnings:

(a) Of the direction lever 30 on the tilting of the wings;

(b) Of the turning corrector 1 on this same 80 tilting;

(c) Of the palette feeler 90 to the regulation 85 of the angle of entry on the wing, in case of violent wind, in such manner that the turning may be correct under all circumstances.

To this end, the navigating automatic device 90 is provided with regulating mechanisms permitting the value of the action of each of these devices which act in common to be exactly determined.

As regards the automatic navigation of the 95 aeroplane in depth, the various manœuvres for re-establishing longitudinal equilibrium also find their point of support on the horizon base produced by the gyroscopic group placed in equilibrium on the three dimensions of space. The braking of the pitching of the aeroplane about its centre of gravity is effected automatically by the horizon base which acts as an indicating member of the 100 righting and controls the depth rudder at 105 the proper moment.

But, in order that the depth navigation 110 may be effective, it is indispensable to add to the horizon base a "loss of speed signaller" 115 which causes the diving of the aeroplane before the thrust and the drag which support it in the relative wind have attained their minimum critical limit, below which, the aeroplane being too lightly supported, would commence to fall or to slip on the wing. The 120 loss of speed signaller being subjected to a horizon base, its actual front of entry into the eye of the wind is always in a position entirely free and independent of the longitudinal angle of entry of the aeroplane into the same relative wind. Consequently, if the thrust and the pull which sustain the aeroplane in the relative wind are insufficient to support it, the loss of speed signaller effects 125 an immediate action of the depth rudder 120

which causes the aeroplane to dive owing to their insufficiency to increase its relative speed.

Furthermore, in consequence of a special device, this dive of the aeroplane is the more marked the larger is the angle of entry of the aeroplane in rising. It also becomes more marked in the course of turning by reason of the centrifugal force acting on the aeroplane.

To obtain this result, the loss of speed signaller comprises two distinct devices of which one registers the value of the thrust F and the other that of the pull T , the component of which keeps the aeroplane in equilibrium in the relative wind.

The first device (Fig. 2) comprises:

A reduced model aeroplane 115, the profile of the supporting wing of which and the centre of the thrust of this wing are identical with the profile of the wing and the centre of thrust of the aeroplane which is automatically navigated. On this reduced model, exactly in the centre of thrust, is situated a pivoting axis 116 which permits it to hold itself in a stable position in the eye of the wind, and to register exactly the value of the thrust P which is exerted on the aeroplane. The axis 116 is placed at the extremity of a beam 117 pivoted at 118, and the socket of which carries two opposite levers 119, 119' on which are connected the attaching wires 120, 120' which connect it to another double lever 121 placed on the automatic navigating apparatus. This double lever 121 therefore registers the displacement of the beam 117 and, consequently, the thrust P exerted on the small aeroplane 115. On the socket of the double lever 121 is keyed a rod 122 which is inclined by 30 to 45° to the horizon when the aeroplane is itself in a horizontal line of flight, the incidence α^2 of the rod 122 being variable according to the design of the aeroplane to be stabilized. On this rod 122 is placed a mass 123, the weight of which counteracts the thrust P projected on the horizontal, up to the limit useful for supporting the aeroplane in the horizontal flight. The double lever 119 is prolonged by the rod 119' which slides in a slide 124, which permits it to move back when the thrust P is not sufficient to support the aeroplane, but which limits its travel when this thrust P is normal, or even in excess. Consequently, if the minimum thrust corresponding to the limit of speed in the relative wind necessary to support the aeroplane is not obtained, the beam 117 under the influence of the mass 123 which rocks towards 125' falls towards 125 on the horizon base with which it is always in accord, as will be hereafter shown.

On the other hand, the mass 123, the rod 122 of which is inclined to the horizon, acts more strongly on the beam 117, the greater is the angle of entry α of the aeroplane in mount-

ing, for the angle α^2 of the rod 122 to the horizon diminishes in proportion as the elevation of the aeroplane in mounting becomes more accentuated.

As the loss of speed of an aeroplane is all the more dangerous the greater the incidence of its angle of entry in mounting, this device has for effect to act and to right the aeroplane by advancing the limit of dangerous speed in proportion as the aeroplane is upturned. It does not act when the aeroplane dives, which does not afford any use, but, on the contrary, it still registers the loss of speed when the resistance of the wing, which diminishes in proportion as it is elevated, reduces the support of the aeroplane which can only be stabilized by an excess of speed. It is the same when the aeroplane is at the maximum altitude. Furthermore, the centrifugal force which obliges the aeroplane to increase its importance and consequently its relative speed in the course of turning, will also act on the mass 123 and on the device indicating loss of speed 115—117 to produce the dive of the aeroplane in the course of turning as a function even of this centrifugal force.

The loss of speed signaller is completed by a drag indicator although this is not indispensable. This drag indicator is composed of the fuselage 126 having the fineness of the polar of the supporting planes of the aeroplane stabilized. It consequently registers the value of the drag T of this aeroplane. This fuselage 126 remains constantly in the eye of the relative wind by the plane 127 and by its mounting on a trunnion 128 which is fixed at the top of a road 129, 129', which pivots at 118, and the rotation of which is transmitted to the double lever 131, 131' by the connecting wires 132, 132'. The movement of the rod 129' is limited for a normal trail or an excess one, by being keyed to the bottom of the slide 133, but it can move in this slide if the drag T necessary to support the aeroplane, weakened beyond the dangerous limit, for this limit is determined by the weight of the mass 180, in projection to the horizontal, in consequence of its position on the rod 134 which is inclined by 30° to 45° to the horizon, similarly to the rod 122 of the thrust indicator.

Now, if the aeroplane flying in a straight line according to the arrow 135 pitched towards 136, the double differential 137, 138, 139, 140, 141, which is similar to those previously described for the lateral direction and stability, the planetarium 137, showing the horizon base, will act under the same conditions as these. The contact arm 142 is therefore insensitive to the pitching of the aeroplane, while the contact sector 143 is carried in the pitching movement towards 144. The current passing between the contact 146 and the contact arm 142, excites the depth Servo-motor 149 which acts on the depthrud-

der 150 moving it towards 151 up to the extent of the rotation of the contact sector 143, towards 145, in consequence of the displacement of the operating rod system 153 towards 154, this rotation being proportional to the pitching.

When the pilot desires to lift the aeroplane towards 136, using the automatic navigating apparatus, he draws the depth lever 156 towards 157. The oscillating arm 158 being pushed towards 159, the satellite 140 pivots towards 170, carrying with it the contact arm 142 towards 144, thus putting it in contact with the contact 147. The Servo-motor 149 then excited, moves the depth rudder 150 towards 152 until the moment when the angle of entry α of the aeroplane, having the same incidence as the angle α^1 of the depth lever 156, the depth rudder 150 is again in the position of rest. All these operations are carried out in connection with the horizon base, the latter intervenes each time that the angle of entry of the aeroplane varies with respect to the angle of entry which the pilot has given to the depth rudder 150. The loss of speed signaller which registers on the one hand the limit of thrust P, and on the other hand the limit of drag T dangerous for the stability of the aeroplane, can then intervene efficiently in combination with the horizon base, even when the aeroplane is mounting, to prevent the loss of speed and making it dive in good time and without this horizon base ceasing to intervene if the aeroplane exceeds its position of equilibrium in one direction or the other. For this purpose, the double levers 121, 121' and 131, 131' being respectively keyed on to the planetaria 161, 162, any rotation of these levers towards 163, 163' is communicated to the rods 164, 165 which move towards 166, 166'. The oscillating arm 167 being drawn in the same direction, and the planetarium 137 of the horizon base being in a stable position, causes the satellite 138 to pivot towards 168, the double planetarium 139 towards 169, the satellite 140 towards 172, and the planetarium 141 and the contact arm 142 to which it is attached, towards 173 and 145. The contact 146 being excited, forces the Servo-motor 149 to act on the depth rudder 150, moving it towards 151, producing the dip of the aeroplane in depth 150 towards 151, causing the dip of the aeroplane in proportion to the loss of speed, and this under all the positions which the aeroplane can occupy, but principally when it turns, and when it is upturned, for the indication of the loss of speed is particularly sensitive when the aeroplane is mounting, or making a turn.

The action of the masses 131 and 180 is the more efficient the more the angles α^2 and α^3 are reduced, and the greater are the centrifugal forces 125 and 180¹ which are exerted on them in the course of turning, all condi-

tions which cause the righting members to intervene and prevent the fall of the aeroplane by loss of speed by reason actually of the danger which this loss of speed presents in consequence of the position of the aeroplane. The latter must therefore have a very marked excess of power to permit it to turn while ascending.

On the other hand, it is evident that, in order that the above-mentioned automatic navigation devices may act under satisfactory conditions, it is supposed that the aeroplane has sufficient motive power available, if not, the action of the automatic controls not being sufficiently efficient, the aviator must manoeuvre correspondingly.

What I claim and desire to secure by Letters Patent of the United States is:—

1. In an aircraft, means for automatically operating the lateral control surfaces comprising a gyrostat and compensating means for acting in opposition to said gyrostat under the action of centrifugal force during turning movement of the aircraft for tilting the said lateral control surfaces to bank the aircraft at the necessary angle to perform a correct turning movement.

2. In an aircraft, means for automatically operating the lateral control surfaces comprising a gyrostat and compensating means comprising a mass having a limited sliding motion transversely of the aircraft under the action of centrifugal force during turning movement of the aircraft and acting in opposition to said gyrostat to oppose any movement of the lateral control surfaces due to the action of the gyrostat in a banked turn.

3. In an aircraft, means for automatically operating the lateral control surfaces comprising a gyrostat in combination with a blade disposed vertically in the line of flight of the aircraft and pivotally mounted so that it can be deflected from side to side by side pressure of the air and means for connecting the blade to the mechanism for operating the lateral control surfaces, the blade being connected to the gyrostat so that it is always maintained in a vertical position.

4. In an aircraft, means for automatically operating the control surfaces during normal flight of the aircraft in combination with a pivotally mounted aerofoil arranged in the line of flight of the aircraft and arranged to operate the elevators of the aircraft in the event of the speed of the aircraft falling below a certain point in combination with an auxiliary aerofoil operating in conjunction with the main aerofoil and for registering the drag of the aircraft, the auxiliary aerofoil being connected with the main aerofoil.

5. In an aircraft, lateral control surfaces, and means to automatically operate the lateral control surfaces, said means comprising a gyroscopic group creating the horizon base and compensating means to act conjointly

with the said group under the action of centrifugal force during the turning of the aircraft to tilt the said lateral control surfaces and impart to the aircraft the necessary angle 5 of attack in order to carry out a correct turning, said compensating means comprising a mass movable in the lateral direction of the aircraft under the action of centrifugal force during the turning of the aircraft, and means 10 yieldably opposing such movement of said mass.

6. In an aircraft, control means comprising a gyroscopic group creating the horizon base and mounted in pendulum fashion, and 15 compensating means comprising a mass in connection with the gyroscopic group and movable in the lateral direction of the aircraft under the action of centrifugal force during the turning of the aircraft to compensate the effects of centrifugal force acting 20 on the gyroscopic group, and means yieldingly opposing such movement of said mass.

7. In an aircraft, lateral control surfaces, and means for controlling said surfaces including 25 a gyroscopic group creating the horizon base and a blade feeler arranged vertically in the line of flight of the aircraft, said blade feeler being mounted pivotally to turn laterally under pressure of the air, and operating mechanism for the control surfaces affected by said feeler in conjunction with the gyroscopic group to insure correct banking 30 of the aircraft with respect to the strength and direction of the wind in which 35 the aircraft is flying.

8. In an aircraft, lateral control surfaces, and means for controlling said surfaces including a gyroscopic group creating the horizon base and a blade feeler arranged vertically 40 in the line of flight of the aircraft, said blade feeler being mounted pivotally to turn laterally under pressure of the air, operating mechanism for the control surfaces affected by said feeler in conjunction with the 45 gyroscopic group to insure correct banking of the aircraft with respect to the strength and direction of the wind in which the aircraft is flying, the blade feeler being also mounted for adjustment about an axis extending longitudinally of the machine, and connecting means between the gyroscopic group and blade feeler whereby the vertical 50 position of the latter is constantly maintained.

55 9. In an aircraft, an elevator, and means for automatically operating the elevator during flight of the aircraft, said means comprising a gyroscope group creating the horizon base, operating connections between said 60 gyroscopic group and the elevator, a movable surface mounted in the line of flight of the aircraft and being maintained in a normal position by air pressure during normal flight of the aircraft, means associating said 65 surface with said operating mechanism

whereby upon movement of said surface due to loss of flying speed the operating mechanism is affected to depress the elevator, an auxiliary movable surface subjected to air 70 resistance to register the drag of the aircraft, and connecting means between said surfaces whereby the auxiliary surface acts in conjunction with the first-named surface.

10. In an aircraft, lateral control surfaces; and means for controlling said surfaces comprising a gyroscopic group creating a horizon base, a manually operable lever, a centrifugally controlled turning corrector, and a blade feeler pivoted on a vertical axis in 75 the line of flight of the aircraft; a control lever for determining the range of movement of said control surfaces, and coordinating mechanism including two pairs of opposed bevel gears, one gear of one pair being connected to one gear of the other pair, the other gear of one pair being in connection with the gyroscopic group, said control lever being connected to the other gear of the other pair, satellite pinions respectively engaging 80 the gears of said pairs of gears, a connection between said manually operable lever and one of said satellite pinions, and a connection between the turning corrector and blade feeler and the other of said satellite pinions.

11. In an aircraft, lateral control surfaces; and means for controlling said surfaces comprising a gyroscopic group creating a horizon base, a manually operable lever, a centrifugally controlled turning corrector, and a blade feeler pivoted on a vertical axis in 85 the line of flight of the aircraft; a control lever for determining the range of movement of said control surface, and coordinating mechanism including two pairs of opposed bevel gears, one gear of one pair being connected to one gear of the other pair, the other gear of one pair being in connection with the gyroscopic group, said control lever being connected to the other gear of the other pair, satellite pinions respectively engaging 90 the gears of said pairs of gears, a connection between said manually operable lever and one of said satellite pinions, and a connection between the turning corrector and blade feeler and the other of said satellite pinions. 95

100 12. In an aircraft, lateral control surfaces; and means for controlling said surfaces comprising a gyroscopic group creating a horizon base, a manually operable lever, a centrifugally controlled turning corrector, and a blade feeler pivoted on a vertical axis in the line of flight of the aircraft; a control lever for determining the range of movement of said control surface, and coordinating mechanism including two pairs of opposed bevel gears, one gear of one pair being connected to one gear of the other pair, the other gear of one pair being in connection with the gyroscopic group, said control lever being connected to the other gear of the other pair, satellite pinions respectively engaging 105 the gears of said pairs of gears, a connection between said manually operable lever and one of said satellite pinions, and a connection between the turning corrector and blade feeler and the other of said satellite pinions, said last named connection including differential gearing coordinating the movements of the turning corrector and blade feeler and having a satellite whose angular movements 110 are imparted to the last-named satellite pinion. 115

120 13. In an aircraft, an elevator, and means for controlling the elevator; said means comprising a gyroscopic group creating the horizon base, a loss of speed indicator, and a manipulatable lever; a control lever for determining the range of movement of said elevator, and coordinating mechanism including two pairs of opposed bevel gears, one gear of one pair being connected to one 125 130

- gear of the other pair, the other gear of one pair being in connection with the gyroscopic group, the other gear of the other pair being connected to said control lever, satellite pinions respectively engaging the gears of said pairs of gears, a connection between said indicator and one of said satellite pinions, and a connection between said manipulatable lever and the other of said satellite pinions.
- 5 13. In an aircraft, control surfaces therefore, and control means for the control surfaces, said control means comprising a gyroscopic group creating the horizon base and direction reference, connections between the
- 10 15 gyroscopic group and control surfaces including a clutch, two manually operable direction controllers operable on the control surfaces through said connections, and means operated upon initial movement of one of
- 15 20 said controllers to disengage said clutch.
